UNITED STATES PATENT OFFICE.

WARREN M. HEALEY, OF NEW YORK, N. Y.

DESIGN FOR A DOOR-HANDLE.

51,961.

Specification for Design.

Patented Apr. 9, 1918.

Application filed February 6, 1918. Serial No. 215,708. Term of patent 3½ years.

To all whom it may concern:

Be it known that I, WARREN M. HEALEY, a citizen of the United States, and a resident of the city of New York, borough of Manhattan, in the county and State of New York, have invented a new, original, and ornamental Design for a Door-Handle, of which the following is a specification, reference being had to the accompanying drawings, forming part thereof.

I claim:—

The ornamental design for a door handle as shown.

WARREN M. HEALEY.
